FIG. 2

FIG. 1

FIG. 3

FIGURE 1 is a top plan view of a wall decoration or the like showing my new design;

FIGURE 2 is a perspective view;

FIGURE 3 is a bottom plan view;

The fragmentary broken line showing of flowers and the like in FIGURES 1 and 2 is for illustrative purposes only.

The characteristics of this novel design reside in the arrangement of the truncated cone-like members and cylindrical members radiating on a circular base board. The central portion is open and adapted to receive an ornament such as an arrangement of flowers or fruit, the latter being shown in part in dotted lines in FIGURES 1 and 2.

I claim:

The ornamental design for a wall decoration or the like, substantially as shown and described.
